UNITED STATES PATENT OFFICE.

CHARLES A. BUCKLIN AND JOHN D. KNOWLTON, OF CAMDEN, MAINE.

WINDLASS.

SPECIFICATION forming part of Letters Patent No. 276,956, dated May 1, 1883.

Application filed March 13, 1883. (No model.)

To all whom it may concern:

Be it known that we, CHARLES A. BUCKLIN and JOHN D. KNOWLTON, of Camden, in the county of Knox and State of Maine, have invented a new and useful Improvement in Windlasses; and we do hereby declare that the following is a full, clear, and exact description of the same.

Our invention relates to improvements in windlasses; and the invention consists in improved locking devices for securing the wild-cat to the pawl-wheel, and for disconnecting the wild-cat to let it run free.

In its general features our invention comprises a large wheel having ratchet-teeth on its periphery, and keyed upon a driving-shaft, a wild-cat running loosely on the shaft, and a sliding catch operated by a cam mounted on the ratchet-wheel, and engaging with notches in a flange or rim of the wild-cat.

The invention also comprises various details of construction, which will be more fully hereinafter explained.

In the drawings, Figure 1 is a central longitudinal section; Fig. 2, a cross-section on the line *xx*; Fig. 3, a front view of the ratchet-wheel with the bearing-plate removed; Fig. 4, a similar view. Fig. 5 is a front elevation of a modified form.

30 A represents the driving-shaft, mounted in suitable standards and adapted to be rotated by power from any convenient source. At about the middle of this shaft is keyed or otherwise fixed the large wheel B, which has a peripheral ratchet, with which engages any ordinary style of pawl. The wheel B is formed with a cylindrical projection, C, over which fits the flange or rim *a* of the wild-cat D. The wild-cat is mounted loosely on the driving-shaft. In the face of the projection C is formed a slot, *b*, which communicates with a circular chamber, *c*, extending entirely through the wheel B. In this chamber is a shaft, *d*, which projects beyond the wheel B, and has at or near its end holes *ee*, for the insertion of a lever. The opposite end of shaft *d* extends into the space formed by the slot *b*, and upon it is mounted an eccentric, *f*. Surrounding the eccentric, and fitting closely within the slot *b*, is a strap, *g*, with which is formed a dog or bolt, *h*. The end of the shaft *d* is journaled

in an opening in a plate, *i*, which closes the slot, and also forms a stop for the shoulder *j* of the bolt *h*. The rim or flange of the wild-cat is provided with notches *kk*, and as such rim projects over the part *C* of the ratchet-wheel, the bolt *h* is adapted to enter one of such notches, and thereby lock the wild-cat to the ratchet-wheel and driving-shaft. This is accomplished by turning the shaft *d* in either direction by means of the lever, the movement of the cam causing the bolt to project beyond the edge of the chamber which holds it. When at its lowest position and resting on the stop-plate, the end of the bolt is flush with the periphery of the part *C*.

In Fig. 5 we have shown a modified form of our device. In this case a spur-wheel, *l*, is keyed upon the projecting end of the shaft *d*. With this wheel engages a similar gear-wheel, *m*, loose on the driving-shaft and having a flange, *n*. Upon the flange *n* are projecting studs *oo*, arranged in circles near the edge, by means of which and a suitable lever the gear-wheel *m* can be turned. It will readily be seen that as the gear-wheel *l* is mounted on the shaft of the eccentric motion of the flange *n* in either direction will operate the bolt and lock or unlock the wild-cat. The flange *n* and gear-wheel *m* are held in place upon the driving-shaft by a collar, *p*, and screw *q*.

By the use of this mechanism the wild-cat can be instantly disconnected from the driving-shaft under any strain and as quickly connected, and when the driving-shaft is in any position.

What we claim is—

1. The combination, with the ratchet-wheel and with the loose wild-cat, of a sliding bolt and an operating-eccentric mounted in the ratchet-wheel and adapted to engage with the wild-cat.

2. The combination of the driving-shaft, the ratchet-wheel keyed thereon, the loose wild-cat having a notched rim, a cam-shaft mounted in the ratchet-wheel, and operating a sliding bolt which engages with the notched rim of the wild-cat.

3. The combination, with the chambered ratchet-wheel and with the flanged wild-cat, of the shaft *d*, the eccentric, the strap, and the sliding bolt connected to such strap.

4. The chambered ratchet-wheel, in combination with the shaft, the cam, the sliding bolt, and the perforated stop-plate.

5. The chambered ratchet-wheel, in combination with the shaft, the cam, the sliding bolt, the perforated stop-plate, and the spur-gear, flange *n*, with the projecting studs, and lever, by means of which the sliding bolt and cam are operated.

In testimony whereof we have signed our names to this specification in the presence of two subscribing witnesses.

CHARLES A. BUCKLIN.
JOHN D. KNOWLTON.
